UNITED STATES PATENT OFFICE.

FRANCIS H. RICHARDS, OF SPRINGFIELD, MASS., ASSIGNOR OF ONE-HALF
TO THE PRATT & WHITNEY COMPANY, OF HARTFORD, CONN.

ENVELOPE-BLANK-FEEDING MECHANISM.

SPECIFICATION forming part of Letters Patent No. 340,245, dated April 20, 1886.

Application filed January 31, 1885. Serial No. 154,578. (No model.)

To all whom it may concern:

Be it known that I, FRANCIS H. RICHARDS, a citizen of the United States, residing at Springfield, in the county of Hampden and State of Massachusetts, have invented certain new and useful Improvements in Envelope-Blank-Feeding Mechanisms, of which the following is a specification, reference being had to the accompanying four sheets of drawings, in which—
10 Figure 1 is a plan view of a mechanism embodying my invention. Fig. 2 is a front elevation of the same. Fig. 3 is a plan view, partly in section, the top plate and the parts thereon being removed. Fig. 4 is a vertical section in line *a a*, Fig. 1. Fig. 5 shows the relation of certain details as seen from the back side of the machine, this being at the right hand in Fig. 4.

Similar characters designate the same parts 20 in all the figures.

This invention relates to that class of blank-feeding mechanisms in which the pile of blanks is replenished at the bottom while the pickers are taking blanks from the top thereof.

25 The object of the invention is to provide improved mechanism whereby that operation may be conveniently performed and each blank-supporting plate may be operated independently of the other.

30 To this end my invention consists in certain improvements and combinations, which will first be described in connection with the drawings, and afterward pointed out in the claims.

Referring to the drawings, *A* designates the 35 frame-work of this mechanism, which may be a projecting or other part of the frame of an envelope-machine, and is conveniently made box-shaped, as shown, to contain the intermediate shafts and gearing.

40 *A*² is a top plate, which forms the cover of frame *A*, and to the top of which the usual guides are fixed for holding the blanks in proper position laterally. These guides are four in number, arranged in two pairs, of which 45 one is at the front, (marked *G*,) and one at the back, (marked *G*².) All of these guides usually have a slight adjustment on the top plate, being held down by screws 2 and washers 3, which washers are clamped by the screws onto 50 the base 5 of each guide. The front guides each consist of the base 5, a post, 6, rising from

said base, a laterally-projecting arm, 7, and the aforesaid guide *G*, attached to said arm, these parts being separate pieces connected together or made in a single piece, as may be preferred. 55 The back guides, *G*², rise directly from their bases, but have in this case, as they usually do in practice, an outwardly-projecting arm, 8, Fig. 1, for holding the separator device. This device consists of an arm or lever, 9, pivoted to said arm 8 at 10, and provided with separator-fingers 11, which may be clamped therein by screws 12. Springs 13 are provided to produce a slight downward pressure of the fingers onto the pile of blanks, being fixed to 60 arms 8 and 7, and having points 14 bearing on said levers 9. (See Figs. 1 and 2.)

P designates a pile of envelope-blanks in proper position for the gummer *J* to take up blanks therefrom, the pile, as shown, being 70 nearly exhausted.

B is one of the blank-supporting plates, shown in position for holding up pile *P*, and at the uppermost point of its vertical travel. *B*² is a similar blank-supporting plate, (shown 75 in dotted lines in Figs. 1 and 2,) which is shown in position for receiving the pile of blanks *P*². These blank-supporting plates are respectively each upheld by a similar set of vertically-movable plate-lifters, *R* and *R*². 80 Each set of lifters consists of three rods arranged in a triangular form, as shown in Figs. 1 and 3.

For communicating a simultaneous and equal vertical motion to all the lifters in a set, a 85 horizontal rod, *M*, for lifters *R*, and *N* for lifters *R*², is provided and arranged to slide in bearings formed in the frame.

Underneath and at right angles to rods *M* and *N* are the revolving shafts *S*² and a fixed 90 shaft, *S*, carrying a system of gearing intermediate to said rods and lifters. Each rod has rack-teeth 15 upon it, which mesh into a gear on shaft *S*, and into another on shaft *S*².

In Fig. 3 a part of rods *M* and *N* is broken 95 away the better to show the arrangement of the gearing. Rod *M* meshes into gear 16, which is fixed on shaft *S*, and into gear 17, which revolves loosely on shaft *S*². Shaft *S* has two gears, 18 and 19, each of which meshes 100 into rack-teeth on one of the front lifters *R*, (see Fig. 3,) and gear 17 has secured thereto a

gear, 20, which meshes into similar rack-teeth on the rear lifter R. Rod N meshes into gear 21, (similar to gear 16,) which is loosely fitted on shaft S between collars 22, and into gear 5 25 on shaft S², which is similar to gear 17. Gear 21 has fixed thereto a gear, 24, which meshes with another and similar one, 26, fixed on shaft S². This shaft has two gears, 27 and 28, fixed thereon, each of which meshes into 10 rack-teeth on one of the front lifters R², and gear 25 has another, 29, (similar to gear 20,) which meshes into rack-teeth on the rear lifter R². The relative proportions of the members of these systems of gearing are such that when 15 either of the rods M and N are drawn forward the set of lifters connected thereto will all be raised up equally. It is desirable, also, that said rods shall move somewhat faster than the lifters, so that the operator can control the 20 elevation of the pile with greater ease and accuracy.

I do not limit my invention to such gearing having precisely the arrangement described, for this may be modified in several ways; but 25 the said arrangement is the best one that I have thus far been able to discover.

The rods M and N have ratchet-teeth 30 on their upper sides, whereby they are automatically fed forward. For this purpose a rock- 30 shaft, S⁴, carried on brackets K, and having arms 31, is provided with feeding-pawl 32, and with holding-pawl 33, which operate in the usual manner. Said shaft has an oscillating motion imparted thereto through connecting-rod 34 and arm 35, from some suitable 35 member of the envelope-machine, of which this blank-feeding mechanism may in any particular case form a part. The extent of said motion should be sufficient to move pawl 32 40 through the distance of one of the teeth 30, and a little in excess to insure certainty of action. The rods M and N are each provided with a handle, H, whereby they may be operated by hand. Said rods have been de- 45 scribed as having a horizontal sliding movement, but they may also have, and as herein shown do have, a rotary motion of about ninety degrees for the purpose of disengaging pawl 32 from notches 30, handle H being then in 50 position H², Fig. 5. In order that said rotary motion may not also disengage said rods and the gears 16 and 21, the rack-teeth 15 are made to extend around these rods somewhat more than one-fourth of their circumference, 55 as shown in the section of rod M at X, Fig. 3. By turning rod M in the direction there indicated by the arrow teeth 30 are turned down to one side and surface 40 brought under the feeding and holding pawls. Then said rod may 60 be moved by hand forward or backward at any point of its stroke and thrown into engagement with the pawls by simply turning it back to its original position—that is, with handle H hanging down, as in Figs. 2 and 4. Rod M 65 is shown in the drawings in its extreme forward and rod N in its extreme rearward position. At its back end teeth 30 are cut away

at 41, so that pawl 32 cannot feed said rod any farther, thus making an automatic stop-motion to limit the feeding up of plate B. In 75 its extreme backward position the forward notch, 42, of notches 30, stands at 41, (see Fig. 4,) so that the pawls (since they touch a smooth part of the rod) cannot feed along the rod at all until it has first been drawn forward a short 75 distance by hand. By this means the operator can more conveniently place the plate B² and the pile of blanks P² in position.

The blank-supporting plates may have any shape to adapt them for being upheld by the lifters and for holding the pile of blanks, said shape depending somewhat, of course, on the shape of the blanks they are to hold. In Fig. 1, B represents a convenient form for these plates, having fingers 44 for supporting 80 the end flaps, 45. Springs J² (shown in dotted lines in Fig. 1) are fixed to the under side of the plates, to hold them with some little force to their proper position on the top of the lifters by clasping the sides of said lifters, 85 substantially as indicated at 46.

J designates gummers attached to a cross-bar, Z, which is fixed on the lower end of the upright Y. These parts J Z Y are or may be the same as the parts so designated in 95 United States Patent No. 221,835, dated November 18, 1879, to which reference may be had. Upright Y corresponds to "picker a," and shaft S² to "shaft 8" in United States Patent No. 284,483, granted to me September 4, 100 1883, and for automatically operating said shaft from said upright or picker I may employ, in connection with my present improvements, substantially the same mechanism as shown and described in my said patent. 105

The operation of my improved envelope-blank-feeding mechanism is as follows: One of the blank-supporting plates, as B, is placed in position B² on the lifters R, which then stand down. A pile of blanks, as P, is then placed on plate B, and the plate with said pile on it is lifted up till the top of said pile is at the point shown in Figs. 2 and 4. The envelope-machine being now started up, the blanks are taken one at a time from the top 110 of the pile, the plate being fed up in the meantime by means of the mechanism described. While this is going on, the operator places plate B² in position on lifters R², and pile P² placed thereon. Rod N is now drawn forward, lifting-plate B² until pile P² reaches plate B, as at position 50, when this plate is pulled out, letting the remainder of pile P rest on pile P². Rod M is turned to disengage the pawls and slide back, lowering the 115 lifters R, and plate P is again placed on them and another pile of blanks on that, to be fed up as before. In this way the machine may be run continuously, the blanks being fed at 120 convenient intervals.

It should be understood that I am not limited to the use of any particular number of lifters R or R², nor to the use of the spur-gearing shown for connecting them together,

as both may obviously be modified and arranged in various ways without departing from the spirit of my invention.

The sliding rod M and the parts immediately driven by and driving the same constitute a mechanical movement which I have described and claimed in another application, Serial No. 175,823, filed August 31, 1885.

Having thus described my invention, I now claim—

1. The combination of a set of lifters, R, rod M, and connecting-gearing interposed between said rod and set of lifters, substantially as described.
- 15 2. The combination of plate P, lifters R, and springs J², substantially as described.
3. The combination of a plate, as B, vertically-movable lifters upholding said plate, a sliding rod or part, as M, provided with 20 ratchet-teeth, means, substantially as described, for operating said lifters from said part, and a ratchet mechanism, substantially

as described, for operating said part, substantially as set forth.

4. The combination of one mechanism consisting of plate-lifters, and devices, substantially as described, for operating them, with another and similar mechanism consisting of substantially duplicate lifters and devices, said mechanisms being each adapted to be operated 25 independently, substantially as set forth.

5. The combination of one mechanism consisting of lifters R, rod M, and intermediate gearing, substantially as described, with another and similar mechanism consisting of 35 lifters R², rod N, and intermediate mechanism, substantially as described, said mechanisms being each adapted to be operated independently of the other, substantially as set forth, and for the purpose described.

FRANCIS H. RICHARDS.
